UNITED STATES PATENT OFFICE.

WALTER J. STAUSS, OF CINCINNATI, OHIO, ASSIGNOR TO UNION SPECIAL MACHINE COMPANY, OF CHICAGO, ILLINOIS, A CORPORATION OF ILLINOIS.

WAISTBAND FOR TROUSERS.

Application filed January 5, 1925. Serial No. 573

The invention relates to new and useful improvements in trousers, and more particularly to the waist band construction thereof.

An object of the invention is to provide a
5 waist band construction which includes a
stiffening strip and a lining or facing strip,
and wherein said lining strip and stiffening
strip are secured together and to the body
fabric forming the trousers by stitches which
10 are concealed from view at the front of the
garment by the body fabric, and also con-
cealed from view at the inside of the gar-
ment by the facing strip, and wherein there
15 are two lines of concealed stitches, one of
which is located adjacent the upper edge of
the stiffening strip and the other at the
lower edge thereof.

In the drawings which show by way of illustration one embodiment of the invention—

Figure 1 is a sectional view through the body fabric of the trousers, the stiffening strip and the facing strip which have been united by the improved arrangement of concealed stitches, and prior to the folding of the waist band inside of the garment:

Fig. 2 is a similar view but showing the waist band structure folded inside of the body fabric of the trousers, and

30 Fig. 3 is a plan view from the inside of the garment, the several layers being broken away to show the construction of the waist band.

35 The invention is directed broadly to a waist
band construction wherein a stiffening strip
such as canvas or the like, is secured to a
facing strip, and to the body fabric of the
trousers by concealed stitches, that is, stitches
which are concealed from view from the
40 front of the garment and also from the in-
side of the garment. The facing strip has
its edges inturned, and the inturned por-
tions of the facing strip are secured to the
stiffening strip by lines of stitches which pass
45 through the inturned portions only of the
facing strip, so that said lines of stitches
are concealed by the body portion of the
facing strip.

The invention will probably be best understood by a detail reference to the drawings, in which a canvas stiffening strip is indicated at 1. The body fabric of the trousers is indicated at 2, and the facing strip is indicated at 3. One edge of this facing strip is inturned at 4, and this inturned edge is

superposed upon the body portion 2 of the fabric forming the trousers, and the body portion 2 is superposed upon the canvas strip 1. These parts are united by a line of stitches 5 which enter first the inturned portion of the facing strip, and emerge from the outer face of said stiffening strip, where the thread loops forming the penetrating stitches are secured in the ordinary way; that is, either by a looper thread or by an interlocking of the loops which penetrate the fabric parts. The lower edge of the facing strip 3 is inturned at 6. The inturned portion 6 of the facing strip is secured to the stiffening strip 1 by a line of stitches 70 9. These stitches are formed by a series of loops which pass first through an inturned portion 6 of the facing strip and then through the stiffening strip, and the loops are either enchain'd or secured by a looper 75 thread. These concealed stitches are of the type shown in the patent to Higgins No. 1,195,814, granted August 22, 1916. The thread from which the loops are formed lies between the inturned portions of the facing 80 strip and the body portion of the facing strip, and the loops are passed through said inturned portions and the fabric parts to be united thereby. Thus it is that the body portion of the facing will conceal the threads 85 so that they are invisible from the face side of the fabric strip. The body fabric after it has been secured to the waist band is folded to the position shown in Fig. 2, and the stitched parts may be tacked in this 90 position, if desired. The body fabric 2 will conceal the enchain'd loops which lock the needle threads and cause the loops formed therein to secure the parts together.

In a co-pending application, Serial No. 95
570, filed of even date herewith, there is
shown a machine for forming this waist
band and placing the concealed stitches in
the manner above described. The broad
principle embodied in the machine resides in
the fact that the facing strip passes in rear
of the needles which form the line of stitches
to the stitching point. The side edges of the
facing strip are folded around the needles
so that when the facing strip is caused to
move rearwardly away from the needles
after the manner described in the Higgins
patent, the inturned edges only of the fac-
ing strip will be penetrated by the needles.
100
105

From the above it will be apparent that 110

a waist band construction has been provided wherein the waist band can be made and secured to the body portion of the trousers in one operation. Both the upper and lower edges of the waist band being finished and the parts which are united during this operation have their stitches laid so as to be concealed from the front by the body fabric as well as from the inner face by said lining

10 or facing strip.

It is obvious that minor changes in the details of construction and the arrangement of the parts may be made without departing from the spirit of the invention as set forth

15 in the appended claims.

Having thus described the invention, what I claim as new and desire to secure by Letters-Patent, is—

1. The combination with the body fabric
20 of trousers, of a stiffening strip at the waist band of the trousers, said body fabric being folded over the upper edge of said stiffening strip, a facing strip having its upper edge inturned and placed against the inner face
25 of the folded over edge of the body fabric, a line of stitching passing through the inturned portion only of the facing, said fold-

ed over edge of the body fabric, and the stiffening strip, and concealed from view at the outer face of the garment by the body fabric, and at the inner face of the garment by said facing strip, said facing strip at the lower edge thereof being inturned and secured to the stiffening strip by a line of stitches which passes through the inturned portion only of the facing strip and through said stiffening strip, said last-named line of stitches being concealed from view at the outer face of the garment by the body fabric and at the inner face of the garment by said facing strip.

2. In a waist band for trousers, the combination with a stiffening strip of a facing strip, the facing strip having its edges inturned; said inturned edges being secured to the stiffening strip at each edge thereof by a line of stitches, said lines of stitches being passed through the inturned portions of the edges of the facing strip and through the stiffening strip, whereby said stitches are concealed from view by the overlying portion of the facing strip.

In testimony whereof, I affix my signature.
WALTER J. STAUSS.
